International Inc., Rochelle, Ill.

Filed Jan. 21, 1974, Ser. No. 435,255

Term of patent 14 years

Int. Cl. D2—03

U.S. Cl. D2—257

FIG. 1 is a side perspective view of a crocheted hat showing my new design, the crocheting and the interlacing, contrasting panels being continuous throughout the broken line area as indicated, the opposite side being the same as that shown;

FIG. 2 is a top plan view of the knitted hat;

FIG. 3 is a bottom plan view thereof; and

FIG. 4 is a sectional view taken through said hat along lines 4—4 of FIG. 1 looking in the direction indicated by the arrows.

I claim:

The ornamental design for a crocheted hat, substantially as shown and described.
